UNITED STATES PATENT OFFICE.

THOMAS N. RUSSELL, OF CHICAGO, ILLINOIS, ASSIGNOR TO CHICAGO-CLEVELAND CAR ROOFING COMPANY, OF CHICAGO, ILLINOIS, A CORPORATION OF ILLINOIS.

RAILWAY-CAR.

1,336,864.

Specification of Letters Patent. Patented Apr. 13, 1920.

Original application filed January 17, 1916, Serial No. 72,495. Patent No. 1,272,117, dated July 9, 1918.
Divided and this application filed May 27, 1916. Serial No. 100,414.

To all whom it may concern:

Be it known that I, THOMAS N. RUSSELL, a citizen of the United States, residing at Chicago, in the county of Cook and State of Illinois, have invented certain new and useful Improvements in Railway-Cars, of which the following is a specification, reference being had to the accompanying drawings.

My invention relates to railway cars, and 10 it has for one of its objects the provision of a new and improved form of car end structure adapted to be applied either to a new car in the course of its construction or to an old car of either a steel frame or a wooden 15 frame construction. It is one of the objects of my invention to provide in a structure of this type reinforcing and strengthening means for insuring proper rigidity of the end wall of the car. As is well-known in the 20 railway car art, upon the sudden starting or stopping of a loaded car, enormous stresses are brought to bear upon the ends of the car by the shifting of the load and it is essential that the end walls be very strongly 25 constructed and braced if the car is to be maintained for any considerable time in first class condition. To this end I have used an end-closure member reaching from the top to the bottom of the end of the car, provided 30 with means for reinforcing it in order to secure the maximum strength longitudinally of the car, such reinforcing means being in the form of a rib pressed in horizontal position in the end-closure member near its 35 upper edge, such transversely-extending rib being adapted to strengthen the end-closure structure against bowing outward between its side edges, either in connection with an end-plate or independently thereof. The 40 member is held against bowing outward between its upper and lower edges by a plurality of vertically-extending ribs pressed therein adapted to coöperate with the horizontal rib. It is another object of my invention 45 to improve railway cars in sundry details hereinafter pointed out. The preferred means by which I have accomplished my several objects are illustrated in the accompanying drawings and are hereinafter specifically described. That which I believe to 50 be new and desire to cover by this application is set forth in the claims.

This application is being filed as a division of my former application, Serial No. 72,495, filed January 17, 1916, now Patent 55 No. 1,272,117, granted July 9, 1918.

In the drawings:—

Figure 1 is a perspective view showing the end of a car body embodying my improved construction, the roof of the car being omitted;

Fig. 2 is an enlarged fragmentary view, being a section taken on line 2—2 of Fig. 1;

Fig. 3 is an enlarged detail, being a vertical cross-section taken on line 3—3 of Fig. 1; and

Fig. 4 is an enlarged detail, being substantially a cross-section taken on line 4—4 of Fig. 1.

Referring to the several figures of the drawings in which corresponding parts are indicated by the same reference characters,—

10 indicates the end-sill of a car, 11 the end-plate, 12 the ridge-pole, 13 the purlins, 75 14 the side-plates, 15 the side-sheathing, and 16 the floor, all being arranged in any approved manner. As is common in car structures, the end-plate 11 and the horizontally-extending frame parts connected therewith 80 are very firmly braced relative to the end-sill 10 and the horizontally-extending frame parts connected therewith. Inasmuch as this bracing means may be of any suitable type, it is believed to be unnecessary to illustrate it herein.

17—18 indicate sheet-metal end-closure plates arranged side by side transversely of the car having their adjacent edges secured together by a plurality of bolts or rivets. 90 The plates 17—18 are secured to the end-sill 10 in the construction shown by means of bolts 19 passing through the end-sill. Each of the plates 17—18 is provided at its outer edge with a flange 20 turned about 95 the side of the car, being secured in position by bolts 21 passing through the side-sheathing 15 and through the portion of the framework adjacent thereto. The plates 17—18 are provided near their upper edges 100 with a strengthening rib comprising the portions 22—23, respectively. The separately-formed portions of this rib are connected together and reinforced relative to each other.

by means of a reinforcing bar 24 which is secured in position in the separately-formed portions by means of bolts 25. As is shown in Fig. 1, the strengthening rib 22-23 is of varying depth, being of a maximum depth at about the middle of the car. In the construction shown the upper ends of the plates 17-18 are secured to the end-plate 11 by means of bolts 26, a plurality of such bolts 10 being used on opposite sides of the rib 22-23. A facia-plate 27, partly broken away in Fig. 1, is secured to the end-plate 11 overlapping the end-closure plates 17-18.

Each of the end-closure plates 17-18 is 15 provided with a series of strengthening ribs pressed therein, comprising inwardly-directed ribs 28 and outwardly-directed ribs 29 in alternate position whereby a corrugated surface is produced as shown in Fig. 2. By 20 the provision of the vertically-extending strengthening ribs 28-29, the end-closure plates 17-18 are rendered very strong against bowing outward between their upper 25 and lower edges. By the provision of the transversely-extending rib 22-23 pressed in the plates 17-18 and by the provision of the vertically-extending strengthening ribs 28-29, an exceedingly strong and rigid end-structure is provided, the horizontally-extending strengthening rib 22-23 and the vertically-extending ribs 28-29 being adapted 30 to mutually reinforce each other against the strains thereon in the use of the car.

So far as I am aware, I am the first in 35 the art to provide an end-closure plate extending from the top to the bottom of the end-closure structure, having pressed in its upper end a transversely-extending strengthening rib which is adapted to operate with vertically-extending strengthening ribs pressed in such plate for stiffening and strengthening the end structure, and my claims are to be construed accordingly.

What I claim as my invention and desire to secure by Letters Patent is—

1. In a car end, in combination: a plurality of end sheets extending from top to bottom of the car-end frame and laterally secured together and each having a horizontal 50 stiffening rib formed integrally in it adjacent one of its ends and also having a multiplicity of side-by-side vertical corrugations extending substantially from said horizontal rib to near the other end of the 55 sheet; said ribbing and corrugations substantially filling the body of each sheet and tapering off into the plane margins thereon.

2. In a car end, in combination: a pair 60 of end sheets extending from top to bottom of the car-end frame and laterally secured together and each having a horizontal stiffening rib formed integrally in it adjacent one of its ends and also having a multiplicity of side-by-side vertical corrugations 65 extending substantially from said horizontal rib to near the other end of the sheet, the horizontal rib in each sheet meeting the horizontal rib in the other sheet at their 70 meeting edges, so that said ribs form a continuous stiffening member transverse of substantially the full width of the car end; said ribbing and corrugations substantially 75 filling the body of each sheet and tapering off into the plane margins thereof.

3. A box-car end-sheet adapted to extend from top to bottom of the car-end frame and having a horizontal stiffening rib formed integrally in it adjacent one of its 80 ends and having a multiplicity of side-by-side vertical corrugations extending substantially from said horizontal rib to near the other end of the sheet, said rib and corrugations substantially filling the body 85 of the sheet and tapering off into the plane margins thereof.

THOMAS N. RUSSELL.
